Primary Examiner—Robert A Delehanty*(74) Attorney, Agent, or Firm*—Ira S. Dorman(57) **CLAIM**

The ornamental design for a bath water barrier, as shown and described.

DESCRIPTION

FIG. 1 is a rear elevational view of a bath water barrier showing my design;

FIG. 2 is a front elevational view of the bath water barrier shown in FIG. 1;

FIG. 3 is a top view of the bath water barrier shown in FIG. 1; FIG. 4 is a bottom view of the bath water barrier shown in FIG. 1; and,

FIG. 5 is a side perspective view of the bath water barrier shown in FIG. 1.

The broken line showing bottom surface is included for the purpose of illustrating a portion of the bath water barrier that forms no part of the claimed design.
